UNITED STATES PATENT OFFICE.

JAMES M. QUICKE, OF PETERSBURG, VIRGINIA.

ADJUSTABLE INK RESERVOIR FOR PENS.

Application filed March 10, 1924. Serial No. 698,226.

To all whom it may concern:

Be it known that I, JAMES M. QUICKE, a citizen of the United States, residing at Petersburg, in the county of Dinwiddie and State of Virginia, have invented certain new and useful Improvements in Adjustable Ink Reservoirs for Pens; and I do hereby declare the following to be a full, clear, and exact description of the invention, such as will enable others skilled in the art to which it appertains to make and use the same.

The present invention relates to improvements in adjustable ink reservoirs for pens.

The objects of the invention are to provide an adjustable attachment to the ordinary pen whereby the same may be converted into a fountain pen; to provide an attachment that is adjustable and detachable, the attachment having the following characteristics.

It has no connection with the penholder; it is not made part of, or as a fixture attached to a particular pen; it requires no notches, slots, or projections in or on the pen, nor any extra work on pen or device for the purpose of attachment and adjustment to pen; it is adjustable automatically to pen without effort and without alteration in pen or device; it is adjustable automatically to any pen of any shape or size within reasonable limits; it is detachable from one pen and transferable to another with equal ease; it may be removed and replaced with another in case of clogging with dried or gummed ink; it has no effect on the writing qualities of the pen, except increase of capacity; it is neither unsightly nor cumbersome; it is designed for manufacture and sale separately from the pen, and without regard to any particular pen; cost of manufacture will be very small, possibly about ten cents a hundred; not more than two sizes of the device would be required to accommodate all usual sizes and styles of pens; it can be made of celluloid or semi-hard rubber as well as of thin spring metal.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a top plan view of a pen with

the improved attachment mounted thereon.

Figure 2 is an under plan view of the same.

Figure 3 is a side view of the arrangement as shown in Figure 1.

Figure 4 is a longitudinal section taken on the line 4-4 in Figure 1.

Figure 5 is a cross section taken on the line 5-5 also in Figure 1.

Figure 6 is a plan view of the attachment disassociated from the pen.

Figure 7 is a plan view of a pen and attachment showing a slight modification, and

Figure 8 is a longitudinal section taken on the line 8-8 in Figure 7.

Referring more particularly to the drawings and for the present to the preferred form of the invention shown in Figures 1 to 6 inclusive 9 designates generally a pen of the usual or any desired form having a point 10 and the side wings 11 remote from the point and remote from the slot 12 which extends inwardly an appreciable distance from the point 10, the feeding slit 13 being connected to the outer end of the slot 12 and the pen point.

All pens are usually made of this general form, although modifications occur in the way of size, shape and in the position of the slot, etc. The present invention is illustrated alone in Figure 6 and forms an adjustable and detachable accessory in connection with any form, style or size of the pen. This device consists of the tongue 14 and the head 15 provided with the curled spring arms 16. The head 15 and spring arms 16 are preferably of rather narrow material, and the spring arms 16 are rolled in the manner indicated in Figure 5 whereby they may embrace the sides of the wings 11 of the pen and thus hold the attachment on the pen, the tongue 14 being curled upwardly from the head 15 to the pen point 10 or approximately to the point; it being understood that the device is adjustable longitudinally upon the pen. In this way the reservoir can be brought to any desired location with respect to the pen point and the feeding of the ink may be regulated in this way.

The tongue 14 will form a reservoir with the opposed parts of the pen and a considerable body of ink may be retained in this reservoir, the ink being received by merely dipping the pen beneath the surface of the ink. The tongue is preferably wide in the

central portion as shown in Figure 6 and tapers outwardly to agree with the formation of the pen point.

As shown in Figures 7 and 8 the tongue 14' is located upon the top of the pen 9' and the head 15' is provided with similar spring arms 16' except for the fact that these arms are bent downwardly and rolled in the opposite direction to engage within 10 the wings of the pen 9' rather than upon the outside surfaces thereof as shown by the first form of the invention. In addition the tongue may be bent outwardly as indicated at 17 in order to form a space between 15 the pen and tongue to receive an adequate body of the ink.

In operation the pen is simply dipped in the fluid body of ink, it acquiring a large body of ink held in the reservoir, so that 20 resort to the ink well is required only infrequently. The device may be removed at any time and replaced by a fresh device and the arrangement admits of an adjustability which is extremely desirable particularly 25 where the same attachment is used on a large number of styles of pens. The device forms a convenient slip-on attachment in which the adjustment is made by means of springs. The device provides for automatic 30 adjustability to the size and shape of the pen the scope of the automatic adjustment being very wide without diminishing the elasticity of the pen or causing its points to spread. This is accomplished by means of the nar-

row convoluted springs into which the arms 35 are bent for the purposes of attachment and adjustment, since the springs in this form operate laterally, vertically and longitudinally. It is of course understood that the material is very thin and highly resilient. 40 The device has been shown to give excellent results in actual practice.

It is obvious that various changes and modifications may be made in the details of construction and design of the above specifically described embodiment of this invention without departing from the spirit thereof, such changes and modifications being restricted only by the scope of the following claim. 50

What is claimed is:—

An adjustable ink reservoir for pens, comprising a tongue, and a head on the inner end of the tongue, said head having curled spring arms adapted to yieldably and adjustably engage the opposite wings of a pen and support the head across the pen, said tongue being curved inwardly from the head toward the point of the pen to space the intermediate portion of the tongue from the pen and provide a reservoir for ink, said curled spring arms being narrow and the curled spring portions thereof being adapted to bind and rock on said wings of the pen to yieldingly hold the end of the tongue against the point of the pen and adapt the device to pens of various types. 60 65

JAMES M. QUICKE.
